M. M. MARCUSE,
DISPENSING DEVICE FOR SHEET MATERIAL.
APPLICATION FILED MAR. 23, 1920.

1,400,619.

Patented Dec. 20, 1921.

Moses M. Maranee Inventor
By his Attorney
H. Lee Stelzer

UNITED STATES PATENT OFFICE.

MOSES MITTELDORFER MARCUSE, OF NEW YORK, N. Y., ASSIGNOR TO WEST DISINFECTING COMPANY, OF NEW YORK, N. Y., A CORPORATION OF NEW YORK.

DISPENSING DEVICE FOR SHEET MATERIAL.

1,400,619.

Specification of Letters Patent. Patented Dec. 20, 1921.

Application filed March 23, 1920. Serial No. 368,161.

To all whom it may concern:

Be it known that I, MOSES MITTELDORFER MARCUSE, a citizen of the United States of America, and resident of New York city, in the county of New York and State of New York, have invented certain new and useful Improvements in Dispensing Devices for Sheet Material, of which the following is a specification.

10 This invention relates to apparatus for dispensing sheet material, such as paper, and particularly paper toweling, toilet paper, wrapping paper and the like, the apparatus being particularly designed for dispensing material from a web. An object of the invention is to provide a dispenser in which the mechanism is exceedingly simple, so as to reduce the cost of manufacture, and a further object is to provide a dispenser in which 15 the desired length of material may always be withdrawn from the dispenser, without the possibility of the material occupying an inaccessible position.

Further objects and advantages of the invention will appear from the description of the apparatus, and in order that the invention may be more fully understood, reference is made to the accompanying drawings illustrating several preferred embodiments 30 thereof, and in which:

Figure 1 is a central longitudinal section of the dispenser;

Fig. 2 is a cross-section on the line 2—2 of Fig. 1;

35 Fig. 3 is a perspective view of another embodiment of the invention, particularly adapted for large containers adapted to hold a very long web to avoid frequent refilling.

Fig. 4 is a detail view of the embodiment 40 shown in Fig. 3 and

Fig. 5 is a central longitudinal sectional view of another embodiment of the invention.

Referring particularly to Figs. 1 and 2, 45 the dispenser comprises a rear wall 1, top and bottom walls 2 and 3 respectively and side walls 4 and 5. A cover 6 is hinged at 7 to the side wall 4, and this cover is formed with a slot 8. The cover 6 is held in the 50 closed position by means of a lock 9 or other suitable retaining means. A table 10 is hinged to the bottom wall 3 at 11, and this table is preferably (though not necessarily) urged inwardly, by means of a spring 12. 55 The table rests against stops 13 provided on

the side walls 4 and 5. As shown in Fig. 2, the spring 12 may be dispensed with and instead, spring catches 14 may be used. Obviously when the cover 6 is opened, the table 10 may be swung outwardly and downwardly 60 against the action of the spring 12. The tongue 15 is pivoted at 16 to the end of table 10, and this tongue carries on its free end a roller 17. A weight 18 is preferably provided on the tongue, or a spring similar to 65 the spring 12 may be provided at the hinge 16. If desired, both the weight and spring may be dispensed with.

Secured to the bottom wall 3 is a number of U-shaped retaining bars 19. 70

It will be noted that there is a space between the cover 6 and table 10, and this space forms a chute 20. The lower end of the cover is provided with cutting means, such as a series of teeth, or a knife 21. 75

A web or package of paper 22 is contained within the housing, and this web is prevented from falling forward by means of the retaining bars 19 and the tongue 15. The paper is led out over the roller 17, in front 80 of the tongue 15 and into the chute 20. In case the paper does not project out of the chute, it may be forced outwardly by inserting the thumb or finger in the opening 8 and pressing upon the paper inwardly and 85 downwardly against the table 10.

Although I do not limit myself to the particular position in which this dispenser is used, yet I would point out that it is particularly adapted to be used in the vertical 90 position as shown, being preferably hung on the wall by means of the member 23.

Referring particularly to Figs. 3 and 4, it will be noted that the construction of the dispensing mechanism is slightly different 95 from that shown in Figs. 1 and 2. Instead of the table 24 being pivoted or hinged to the casing, this table is secured to the cover 6, by means of flanges or the like 25 depending from the cover. The roller 26 is secured 100 to the cover, to the rear of the chute 20, by means of brackets 27. A tongue 28 is pivoted at 29 to the cover 6, and is preferably provided with a spring 30 to force it against the roller 26, although it is obvious that the 105 spring might be dispensed with and a weight (such as 18 in Fig. 1) used instead.

This construction is particularly adapted for large containers, containing a comparatively long web or strip of material, and in 110

which, as the box is emptied the upper end of the material (see line 31 in Fig. 4) has a tendency to drop back. The spring-forced or weighted tongue 28 rests upon the roller 26 and prevents falling back of the paper.

A modified construction is shown in Fig. 5, in which the portion of the cover 6 formed with the opening 8 is bent downwardly at 32. This portion 32 of the cover has secured to 10 it the plate or table 24, by means of flanges or the like 25. The front wall 3 of the casing is bent inwardly as at 33 to abut against the table 24, and thereby form a curved extension of the chute 20. This construction 15 could obviously be modified, by having table 24 free from the cover extension 32, and integral with the portion 33 of the wall 3.

One of the advantages of the invention herein shown resides in the fact that when 20 the cover 6 shown in Figs. 1 and 2 is opened, and the table and tongue 10, 15, pulled outwardly, the whole side of the box is opened, and it is easy to insert the package or web of material. Then when the package 22 is 25 placed in position, and the dispenser closed, the retaining bars 19 and the tongue serve to keep the package 22 in place.

In the embodiments shown in Figs. 3 to 5, opening the cover 6 completely opens the 30 container inasmuch as the table 24 is secured to the cover, or is integral with the front wall of the container.

Obviously, changes and alterations might be made in the construction herein shown 35 and described, and the invention is not to be considered as limited to the exact construction shown, inasmuch as this invention contemplates any and all constructions coming within the scope of the appended claims.

40. What I claim is:—

1. A dispenser for a folded web of sheet material comprising a material supporting casing, a cover movable relatively thereto, and a table mounted independently of the 45 cover and so coöperating with the wall of said cover to form a delivery chute between the cover and the table.

2. A dispenser for sheet material comprising a material supporting casing, a table 50 hinged thereto, a tongue hinged to said table, said table being limited in its movement inwardly of the casing, and a cover plate hinged to the casing, said plate formed with an opening therein, opposite said table.

55. 3. A dispenser for sheet material comprising a material supporting casing, a table hinged thereto, a tongue hinged to said

table, a roller on said tongue, said table being limited in its movement inwardly of the casing, and a cover plate hinged to the casing, 60 said plate being formed with an opening therein, opposite said table and with cutting means.

4. A dispenser for sheet material comprising a material supporting casing, a table 65 hinged thereto, a tongue hinged to said table, said table being urged inwardly of the casing, and a cover plate hinged to the casing, said plate formed with an opening therein, opposite said table. 70

5. A dispenser as claimed in claim 3, provided with retaining members on the casing.

6. A dispenser as claimed in claim 4, provided with spaced retaining members on the casing. 75

7. A dispenser for a folded web of sheet material comprising a material supporting casing, a cover movable relatively thereto, and having a window formed therein, and a table supported by the casing independently of the cover and coöperating with the wall of said cover to form a delivery chute between the cover and the table, the web being exposed by the window whereby it may be manually advanced through the 80 chute. 85

8. In a dispensing apparatus, the combination with a casing and a cover hinged to one of the side walls thereof, of a table hinged to an end wall of the casing, so that 90 when the cover is swung outwardly to the side, the table may be swung outwardly and downwardly.

9. In a dispensing apparatus, the combination with a casing and a cover hinged to 95 one of the side walls thereof, of a table hinged to an end wall of the casing, and a tongue pivoted to said casing, so that when the cover is swung outwardly to the side, the table may be swung outwardly and downwardly together with the tongue. 100

10. In a dispenser for sheet material, the combination with a casing and a cover hinged thereto, and formed with an opening therein, of a table coöperating with said 105 cover, and a tongue pivoted to said table, said table being adapted, when the cover is opened, to assume such a position as not to close or partially close the casing.

Signed at New York city, in the county 110 of New York and State of New York this 1st day of March A. D. 1920.

MOSES MITTELDORFER MARCUSE.
